(57) **CLAIM**

The ornamental design for a watch band housing, as shown and described.

DESCRIPTION

FIG. 1 is a front perspective view of a watch band housing showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right-side elevational plan view thereof; and,

FIG. 7 is a left-side elevational view thereof.

The broken line showings of logos, wristband, and knobs, where used, are for illustrative purposes only and form no part of the claimed design.

1 Claim, 4 Drawing Sheets
